UNITED STATES PATENT OFFICE.

PEARL K. CROWELL, OF MEMPHIS, TENNESSEE, ASSIGNOR TO FARMERS COMPRESS COMPANY, OF MEMPHIS, TENNESSEE, A CORPORATION OF TENNESSEE.

COTTON-COMPRESS.

SPECIFICATION forming part of Letters Patent No. 730,347, dated June 9, 1903.

Application filed August 14, 1902. Serial No. 119,680. (No model.)

To all whom it may concern:

Be it known that I, PEARL K. CROWELL, a citizen of the United States, residing at Memphis, in the county of Shelby and State of Tennessee, have invented certain new and useful Improvements in Cotton-Compresses; and I do hereby declare the following to be a full, clear, and exact description of the same, reference being had to the accompanying drawings, forming a part of this specification, and to the letters of reference marked thereon.

This invention relates to improvements in apparatus for pressing fibrous materials, the apparatus adopted for illustrating the invention being designed more especially for pressing cotton.

The objects of the invention are to provide a mechanism adapted to be operated economically and by comparatively unskilled labor to reduce the cotton from the loose condition in which it comes from the gin to compact bales of suitable size and weight to be conveniently and economically handled, stored, or transported, the apparatus being especially designed to enable the ginner or planters themselves to put the cotton up in commercial form, whereby the cost and annoyance of rehandling and compressing are avoided.

The invention consists in an apparatus of the character specified wherein the cotton as it comes from the gin is packed in the form of a bale by being projected in successive charges or bats, the preliminary bale so formed being then pressed to the desired degree by hydraulic or other suitable appliances and confined and covered in the ordinary manner to form a commercial bale.

The invention further consists in certain novel details of construction relating to the packing and pressing mechanism and in certain novel combinations and arrangements of the parts, all as will be presently described, and pointed out particularly in the appended claims.

Referring to the accompanying drawings, Figure 1 is a sectional elevation of an apparatus embodying the present improvements. Fig. 2 is a side elevation, but with the parts shown in Fig. 1 omitted. Fig. 3 is a sectional elevation looking toward the right, Figs. 1 and

2, the section being taken on the line 33, Fig. 1. Fig. 4 is a detail section through the press proper and showing the side doors with their operating mechanism, together with parts of the frame. Fig. 5 is a side elevation of the 55 packer. Fig. 6 is a top plan view with portions broken away and omitted. Fig. 7 is a transverse section taken near the feed end of the packer. Fig. 8 is an elevation of one of the cams for holding the bagging or covering 60 for the bale, the view also showing a section of the follower. Fig. 9 is a top plan of the parts shown in Fig. 8, but with the hand-wheel dotted. Fig. 10 is a detail section showing the transfer-head, a portion of the 65 slide, and the means for coupling and uncoupling the two. Fig. 11 is a horizontal section taken on the line 11 11, Fig. 3. Figs. 12, 13, and 14 are detail views of retainers for holding the preliminary bale in the press-box. 70

Like letters of reference in the several figures indicate the same parts.

The main frame of the machine (indicated in the accompanying drawings generally by the letter A) is preferably adapted to contain 75 both the feeding and packing mechanisms for forming the preliminary bale or package and the pressing mechanism for reducing the preliminary package to the desired density, together with auxiliary mechanism for positioning the preliminary package when it is to be pressed. 80

Referring now particularly to Figs. 1 and 3, it will be seen that a conveyer *h* is provided for delivering the cotton, preferably 85 just as it comes from the gin, to a hopper *E*, and from the bottom of the hopper the cotton is discharged by a feeder (to be presently described) into a packing-chamber formed by top and bottom walls *f'*, confined by suitable timbering *f''*, and end walls formed by plates *d d'*. The framing of the packing-chamber extends beyond the chamber for a considerable distance and is independent of the main frame, being pivotally connected 95 with the main frame by a transverse shaft *f''*, whereby the packing-chamber may be swung or oscillated vertically, as indicated by the dotted line *Z*, thereby permitting the feeder to successively feed the cotton over the entire 100

end face of the package. Thus the material is packed in relatively small increments, as will be readily understood.

The end wall or plate d' of the packing-chamber is preferably carried by but adapted to slide longitudinally on the main frame and is curved on its inner face to conform to the arc described by the chamber in its oscillations, while the feed-opening is preferably located near the upper portion of the chamber when at the lower end of its movement. The opposite end wall or plate d is preferably simply guided in the chamber, being capable of a movement toward and from the plate d' , and also in a plane parallel therewith, to guide the package while being transferred from the packing-chamber to the pressing-chamber, as will presently appear.

The plate d forms the face of a packing-follower B^9 , mounted on the forward end of a piston-rod B^{10} , working back into a cylinder B^{11} , preferably of a length corresponding to the length of the packing-chamber. The cylinder may be a pneumatic or a liquid cylinder, and it may be supplied with pressure through a pipe having a stop-cock B^{12} therein. Thus the follower may be advanced by pressure, and when advanced its retreat may be governed by the cock or valve B^{12} , and in operation the material is packed against the resistance offered by the retreating follower, and by regulating the resistance any desired density may be imparted to the preliminary package.

Oscillation may be imparted to the packing-chamber by a crank-shaft g , connected by a yoke or connecting-rod g' with bearings g^2 on the under side of the packing-chamber. The crank-shaft may be rotated by a train of gears g^5 and sprocket-chain g^6 from a shaft g^7 , and the latter may be driven from a shaft B^4 , deriving its motion from a shaft C^6 through gearing B^6 .

The feeding mechanism or the mechanism for forcing the cotton into the packing-chamber and which therefore constitutes a portion of the packer is illustrated particularly in Figs. 1, 5, 6, and 7. From these figures it will be seen that the hopper E discharges into a wide channel, in which is a reciprocating member formed of strips B^2 B^3 , the strips B^3 being of less width than the strips B^2 and alternating therewith. The strips are suitably connected together and reciprocate in the channel B , reciprocating motion longitudinally being imparted thereto by connecting-rods B^7 , connecting a cross-frame B^8 on the reciprocating packer with crank-pins on the wheels B^6 , as shown in full lines in Fig. 6 and in dotted lines in Fig. 5. The forward end of the reciprocating packer travels from a point in rear of the hopper opening into the packing-chamber, and for co-operation therewith to prevent the back expansion of the cotton there is provided a vertically-movable gate formed of triangular blocks b , mounted on a

cross-bar b^5 , which latter is in turn carried by side bars b' , pivoted at b^2 to the sides of the channel-frame B . The blocks b fit into the channels between the bars B^2 and above the bars B^3 , (see Fig. 7,) and vertical oscillatory motion is imparted to the gate by cams b^3 , mounted on the shaft B^4 and so timed as to raise the gate as the reciprocating packer is advanced and to lower the same as the packer retreats.

In operation the portion of the apparatus so far described serves to preliminarily pack the loose cotton in the general form of a bale, and it will be understood that the follower B^9 at the beginning of the operation is close to the feed-opening and is forced back against the resistance of the piston and pressure in the cylinder by the material forced into the packing-chamber by the reciprocating packer, and at the same time the packing-chamber is slowly oscillated past the feed-opening, so as to distribute the cotton evenly over the face of the bale.

Mounted on the main frame and at one side of the packing-chamber (see Figs. 3 and 11) is a pusher or transfer-follower head C , preferably connected with the plate d by a link S and with the plate d , by a detachable coupling formed by a latch d^5 , pivoted at d^2 on the transfer-head and having a hook end d^7 , adapted to engage a stud or shoulder d^6 on the plate d . (See Fig. 10.) The rear end of the latch is adapted to enter a slot d^3 in the main frame when the transfer-head is retracted, as in Figs. 3 and 10, thereby raising the hook end and permitting the same to move back out of the path of the plate d , whereby the packing-chamber is left free to oscillate; but as the transfer-head advances the latch rides out of its slot, and its hook end engages the plate, so as to couple the plate and transfer-follower, both plates and the head then advancing with the preliminary package.

The mechanism for moving the transfer-follower preferably consists of a screw C' , working through a rotary nut C^2 , journaled in the frame and adapted to be rotated by gearing C^3 C^4 from a shaft C^8 . Reverse movement may be given by any ordinary reversing-gear, or the direction of movement of the driving-belt C^5 may be reversed, as will be readily understood.

The pressing or bale chamber is located at one side of the packing-chamber, being formed by the stationary platen D^3 , the movable platen or pressing-follower D^2 , and top and bottom doors D^4 . The follower D^2 is carried by the piston D' of a hydraulic ram or press-cylinder D^{10} , adapted to receive pressure through a pipe controlled by a cock D^9 . The platen D^3 and the cylinder D^{10} are supported by transverse beams A^2 , and the latter are in turn connected by bonds A' to afford the necessary strength and rigidity.

Doors D^4 are pivoted or hinged at D^6 , preferably on axles D^7 , extending, respectively,

beneath and above the platen D^3 , so as to swing up and down, respectively, to permit of access to the bale for covering and binding and also to permit of the discharge of the bale when bound and covered. To retain the doors closed until the follower has advanced the desired distance, slide-bolts D^8 , working in recesses D^5 in the ends of the doors or in fixed parts of the casing m , are employed, said bolts having inturned ends with which the follower engages to withdraw the bolts from the fixed part of the casing as the follower reaches the forward extreme of its movement. The axles D^6 are connected by cross-ties D^7 , preferably extending through the platen D^3 .

Between the packing-chamber and press-chamber suitable guides m' are provided for guiding the preliminary package and plates d d' , between which it is confined. Thus the said package slides smoothly and easily into the bale-chamber without losing its shape and without expanding to any material extent.

Retainers H' H^2 H^3 H^4 are provided for retaining the preliminary package in the bale-chamber when the transfer-follower and plates d d' are withdrawn. Said retainers are pivoted to permit the entry of the package and drop by gravity behind the same, the bottom-retainers H^2 H^4 being provided with counterweights H^8 , by which they are swung into position. The retainers preferably project into the bale-chamber, and in order to permit the press-follower to pass they are provided with lateral inclines H^6 , Figs. 12, 13, and 14, against which said followers will strike to force the retainers back, the retainers again dropping into place when the follower has moved back.

When the preliminary package is pushed into the bale-chamber, it is also pushed into the bagging which is to form the covering for the completed bale. This bagging is placed over the platen and follower D^2 D^3 and with the portions toward the packing-chamber confined beneath cams or holders l , journaled on the platen and follower, respectively, and adapted to be turned by hand-wheels l' on the upper ends of shafts l^2 , so as to clamp the bagging with greater or less pressure. When the bagging is thus held, the preliminary bale or package and the sliding plates d d' may pass within the same and the plates be withdrawn, leaving the bagging in place.

Provision is preferably made for permitting the passage of the retainers through the transfer-follower by forming recesses or notches c^5 in the top and bottom edges of the said follower, as shown in Fig. 1.

In operation the cotton fed by the conveyer h to the hopper E drops through said hopper into the feed-channel and is pushed by the reciprocatory packer into the packing-chamber against the resistance offered by the yielding packer-head B^9 . The packing-chamber is at the same time oscillated vertically past the feed-aperture, thereby distributing the cotton evenly over the face of the bale. When

a sufficient quantity of the cotton has been packed in the packing-chamber and it has been packed to the desired density, the packing-follower B^9 will have moved back into position to engage the catch B^{13} , where it will be held until manually released. The release of the catch B^{13} may be effected by turning the eccentric B^{14} , which bears on the rear end of the catch, as shown in Fig. 1. The mechanism for operating the nut-gear C^2 is then set in motion and the transfer-follower advanced, pushing the preliminary package transversely through the guides m' and into the bale-chamber, where it is retained ready for the pressing operation, while the transfer-head itself, together with the plates d d' , return to normal position. The packing-chamber is now in condition ready for the packing of another charge, and the packing mechanism may be started as soon as the packing-head has been brought forward and the resistance to its retreat adjusted. The hydraulic ram may at the same time be set in operation, forcing up the follower D^2 and compressing the material into a bale of the desired density. When the follower reaches the forward extreme of its movement, it automatically releases the doors D^4 , permitting them to open and expose the bale for the application of the bands and covering material. When pressure in the ram is reduced, the follower is caused to move back to release the bale, preferably by a weight P , connected with the follower by a flexible connection n , passing over a pulley o , although other and well-known means may be employed for this purpose. The released bale drops out of the press-frame through the lower door-opening, and upon the closure of said doors and the resetting of the sliding bolts the press is ready for another operation.

The reciprocatory packer and the gate which co-operates therewith are of simple construction, the former having a solid lower portion, while its upper portion has channels formed by the omission of the upper portions of the alternate strips from which the packer is formed, and the angular blocks of the gate work in these channels, save when the gate is raised for the passage of a charge of cotton. The feed channel and opening may thus be made relatively narrow vertically, and there will be little danger of the packed cotton expanding back, so as to interfere with the operation of the parts or so as to interfere with the correct laying of each charge on the end face, so as to secure a uniform distribution and pressure throughout the bale.

The apparatus as a whole is of simple character, capable of being constructed cheaply, and is well adapted to be placed in the hands of ordinary labor for operation and consequently will answer more perfectly the present-day requirements of a machine which may be owned and operated in proximity to the source of cotton production and from which the finished bales may be shipped di-

rectly to the consumers without the necessity of being first shipped to the compressors and after compression shipped to the consumers.

Having thus described my invention, what I claim as new is—

1. In an apparatus of the character specified, the combination with a packing-chamber, a reciprocatory packer for forcing material into the chamber, a yielding follower against the resistance of which the material is forced into the chamber, and a press-chamber, follower and platen arranged parallel with the packing-chamber, a transfer-follower operating transversely of the packing and press chambers to transfer the preliminary package from one to the other and means for retaining the package under compression while being transferred; substantially as described.
2. In an apparatus of the character specified, the combination with a packing-chamber, a reciprocatory packer for forcing material into the chamber, a yielding follower against the resistance of which the material is so forced, and a press-chamber follower and platen arranged parallel with and to one side of the packing-chamber, of guides between the packing and press chambers, a transfer-follower working transversely from one chamber to the other and driving mechanism; substantially as described.
3. In an apparatus such as described, the combination with an oscillatory packing-chamber, a fixed feed-opening, a reciprocatory packer for advancing material through said opening and a yielding follower against the resistance of which the material is so advanced, of a press-chamber at one side of the packing-chamber, a transfer-follower operating transversely of the chambers to transfer the material from one to the other, guides leading to the press-chamber and with which the packing-chamber registers at one point in its oscillation and driving mechanism; substantially as described.
4. In an apparatus such as described, the combination with the packing-chamber pivoted to oscillate vertically and a yieldingly-supported follower mounted in said chamber to oscillate therewith, of a reciprocatory packer having a relatively narrow feed-opening leading into said chamber, a press-chamber follower and platen and a transversely-operating transfer-follower for transferring the packed material from the packing-chamber to the press-chamber; substantially as described.
5. In an apparatus such as described, the combination with the packing-chamber mounted on a horizontal pivot to oscillate vertically, a pressure-cylinder mounted to oscillate with said chamber and a packing-follower held advanced by the pressure in said cylinder, of a feed-channel, a reciprocatory packer working therein to force material into the packing-chamber against the resistance of the packing-follower, a press-chamber

platen and follower and means for transferring the packed material from the packing-chamber to the press-chamber; substantially as described.

6. In an apparatus such as described, the combination with the oscillatory packing-chamber, means for packing material into the same, means to oscillate said chamber and a press-chamber platen and follower and operating mechanism therefor, of plates forming the end walls of the packing-chamber mounted in ways to move transversely of said chamber and from said chamber to the press-chamber, a transfer-follower for moving said plates and mechanism for moving said follower; substantially as described.

7. In an apparatus such as described, the combination with the frame, the packing-chamber mounted on a horizontal axis to oscillate vertically, the press-chamber, platen and follower and operating mechanism for said parts, of an end plate for the packing-chamber mounted to move transversely of said chamber, a second plate forming the opposite end of said chamber, mounted in ways in the frame to move transversely of said chambers, guides for the plates located on the frame and extending from the packing-chamber to the press-chamber and a transfer-head with connections between said head and plates and means for operating said head to transfer the material held between said plates from the packing-chamber to the press-chamber; substantially as described.

8. In an apparatus such as described, the combination with the frame, the packing-chamber mounted on a horizontal axis to oscillate vertically, the press-chamber, platen and follower and operating mechanism for said parts, of an end plate for the packing-chamber mounted to move transversely of said chamber, ways on the frame for guiding said plate when so moved, a transfer-follower with means for moving said follower to transfer the material from the packing-chamber to the press-chamber and a detachable connection between the plate and transfer-follower whereby said parts are disconnected during the oscillation of the packing-chamber; substantially as described.

9. In an apparatus such as described, the combination with an oscillatory packing-chamber, a press at one side thereof and guides between the packing-chamber and press, of a plate forming the end wall of the packing-chamber, a transfer-follower and operating mechanism therefor for transferring the material from the packing-chamber to the press, a latch for connecting the transfer-follower and plate and means with which the latch cooperates when the said follower is retracted to disconnect the plate and follower whereby the plate is left free to oscillate with the packing-chamber; substantially as described.

10. In an apparatus such as described, the combination with a press-chamber, follower

- and platen with operating mechanism therefor, of a packing-chamber and packer for forcing material into said chamber arranged parallel with and to one side of the press-chamber and a transfer-follower and operating mechanism therefor working transversely through the packing-chamber for transferring the packed material to the press-chamber; substantially as described.
11. In an apparatus such as described, the combination with the press-chamber, follower and platen with operating mechanism therefor, of a packing-chamber, a reciprocatory packer for forcing material into said packing-chamber arranged parallel with and to one side of the press-chamber, guides for the packed material between the packing and press chambers, a transfer-follower working transversely through the packing-chamber for transferring the packed material to the press-chamber, operating mechanism for the said follower and retainers for holding the packed material in the press-chamber when the transfer-follower is withdrawn; substantially as described.
12. In an apparatus such as described, the combination with the press-chamber, platen, follower and operating mechanism therefor, of a packer, means for transferring the packed material transversely into the press-chamber, and pivoted retainers for the packed material projecting into the path of the follower and having transverse inclines with which said follower contacts to move the retainers out of its path; substantially as described.
13. In an apparatus such as described, the combination with the packing-chamber and a feed-channel opening into the same, of a reciprocatory packer working in said channel, and having a continuous bottom portion and grooved upper portion and a gate formed with projections extending into said grooves to prevent the back expansion of the material advanced by the packer; substantially as described.
14. In an apparatus such as described, the combination with the packing-chamber and a feed-channel opening into the same, of a reciprocatory packer working in said channel and formed of alternating narrow and wide strips whereby the upper portion of the packer is grooved and a gate having inclined projections extending into said grooves whereby the back expansion of the packed material is prevented; substantially as described.
15. In an apparatus such as described, the combination with the packing-chamber, a feed-channel opening into the same and a hopper opening into said channel, of a reciprocatory packer working in said channel past the hopper-opening for forcing material from the hopper into the packing-chamber, said packer being formed of parallel alternately wide and narrow strips whereby the top of the packer is grooved and a gate at the discharge end of the channel having blocks with inclined surfaces working in said grooves for preventing back expansion of the packed material; substantially as described.
16. In an apparatus such as described, the combination with a packing-chamber, a feed-channel opening into the same and a gate having depending blocks partially closing the discharge of said channel, of a hopper opening into the channel, means for supplying material to said hopper, a reciprocatory packer working in said channel past the hopper-opening and having grooves in its upper surface into which the projections on the gate may extend and means for elevating said gate as the packer advances; substantially as described.
17. In an apparatus such as described, the combination with the oscillatory packing-chamber, the feed-channel opening into the same, the gate for said channel having wedge-shape depending blocks and a reciprocatory packer working in the channel and having grooves in its surface for the said blocks, of a yielding follower in the packing-chamber, a pneumatic cylinder and piston for holding said follower advanced, a press and a transfer mechanism for transferring the packed material from the packing-chamber to the press-chamber; substantially as described.
18. In an apparatus such as described, the combination with the packing-chamber, the feed-channel opening into the same and the vibratory gate for said channel, of the reciprocatory packer working under said gate and a shaft having a crank connected with the packer for reciprocating the same and a cam for vibrating the gate; substantially as described.
19. In an apparatus such as described, the combination with the packing mechanism and a transfer mechanism for transferring the packed material to a press, of a press at one side of the packing mechanism, guides between the two for the packed material and bagging-retainers located at each side of the channel formed by said guides whereby the bagging may be held in position for the reception of the packed material preliminary to the pressing of said material; substantially as described.
20. In an apparatus such as described, the combination with the packing-chamber, means for packing material therein, a press-chamber arranged parallel with and at one side of the packing-chamber, a platen and follower for the press-chamber and transfer mechanism for transferring the packed material to the press chamber, of vertically-arranged bagging-holders journaled on the frame A adjacent the guides for the packed material and controlling means for said bagging-holders whereby the packed material may be packed into the bagging by the transfer mechanism; substantially as described.
21. In an apparatus such as described, the combination with packing mechanism for forming a preliminary package and transfer mechanism for transferring such package bodily in its packed condition to a press, of a

press having its side toward said packing mechanism open and counterbalanced, doors forming the top and bottom sides of the press; substantially as described.

5 22. In an apparatus such as described, the combination with a packing mechanism for forming a preliminary package and a transfer mechanism for transferring the package in its packed condition to a press, of a press-chamber having its side toward the packing mechanism open, doors forming top and bottom walls of said press-chamber, draw-bolts

for holding said doors closed, a follower for pressing the package and coöperating with said bolts to withdraw the same and allow the doors to open when the follower reaches the inner extreme of its movement and means for operating the follower; substantially as described. 15
